UNITED STATES PATENT OFFICE

2,249,259

ROOM THERMOSTAT

Burton E. Shaw, Bristol, Ind., assignor to Penn Electric Switch Co., Goshen, Ind., a corporation of Iowa

Application May 13, 1940, Serial No. 334,872

2 Claims. (Cl. 200—139)

My present invention relates to a thermostat such as a room thermostat or the like, provided with means to positively retain the switch contacts of the thermostat in open circuit or "off" position when the range adjusting dial of the thermostat is rotated to a predetermined position.

One object of the invention is to provide means to open the circuit through a room thermostat, which means is simple and inexpensive to install on a room thermostat of the usual construction and which utilizes the range adjusting dial thereof as a means to render the circuit opening means effective without the necessity of having an independent switch for this purpose.

A further object is to provide, in a room thermostat having a cam adjusted range mechanism, a bracket secured to a bimetal supporting arm in such manner that it coacts with the switch arm when the cam is adjusted to a predetermined position and positively holds the switch arm against movement to contact closing position.

With these and other objects in view, my invention consists in the construction, arrangement and combination of the various parts of my device whereby the objects contemplated are attained, as hereinafter more fully set forth, pointed out in my claims and illustrated in the accompanying drawing. Although the invention is susceptible of a variety of embodiments, it is unnecessary to fully describe and illustrate more than one in order to give a full understanding of the invention both from its structural and functional standpoints. Accordingly, I have illustrated a preferred and desirable embodiment of the invention in the accompanying drawing, in which:

Figure 1 is a front elevation of a room thermostat embodying my invention and with the cover removed, with the exception of a small portion thereof indicated in section;

Figure 2 is a side elevation from the left side of Figure 1 showing the cover in position and sectioned, and

Figure 3 is a view similar to Figure 1 showing the thermostat adjusted to "off" position.

On the accompanying drawing I have used the reference character B to indicate a base, and C a casing detachably mounted thereon. The casing C supports the usual thermometer tube 10 and may be secured in position by a screw 12.

A pivot screw 13 extends outwardly from the base B and pivoted thereon is a supporting arm A having a short arm 14 and a long arm 15 connected together by a cross arm 16. The arms

14 and 15 are perforated to receive the screw 13 so that the arm A is pivotally mounted with respect to the base.

The arm A carries a coiled bimetal element 17 which may be secured to the cross bar 16 as by rivets 18. The bimetal element 16 terminates in a straight portion 19 which, together with an arm 20, serves as a switch arm. The portions 19 and 20 are connected together by a screw 21.

A stationary contact 22 is mounted in a bracket 23 secured to the base B and a movable contact 24 is adapted to coact therewith. The contact 24 is carried by a leaf spring 25 secured to the switch arm 19—20 by the screw 21. The arm 20 has an armature portion 26 adapted to coact with a permanent magnet 27 for producing snap action of the switch.

An adjusting dial 28 is rotatably mounted on a screw 30^a extending from the base B. The dial 28 has indicia which cooperate with a pointer 29 from the casing C to indicate the various temperatures to which the adjusting dial may be adjusted.

The dial 28 carries a cam 30 coactable with an adjusting screw 31 of the arm A. The screw 31 is threaded in a split flange 32 of the arm.

A spring 33 is coiled around the pivot screw 13 and has a hook end 34 engaging the arm 15. The spring 33 also has a terminal end 35 embedded in a socket 36 in the base B. The spring 33 biases the adjusting screw 31 to contact with the cam 30 in all positions of adjustment of the cam.

A bracket 37 is secured as by rivets 38 to another arm 39 extending laterally from the arm 14 of the supporting arm A. The bracket 37 carries in a split flange 40 thereof an adjusting screw 41. The arm 39 is electrically connected with a terminal 42 by a pigtail connection 43 and a screw 44.

Practical operation

My room thermostat operates in the normal manner when adjusted anywhere between 56° and 85°. In some furnace installations, the thermostat is set back for night operation, whereas in other installations it is desirable to have the burner (normally controlled by the room thermostat) shut off entirely during the night. I have particularly encountered this desirability throughout the West Coast of the United States. Heretofore it has been customary to provide a toggle switch in series with the room thermostat for the purpose of shutting off the burner at night. I have however provided, by means of a

simple bracket 37, mechanism whereby a positive shut-off of the room thermostat may be effected at night.

The dial 28 is adjustable through a range of movement determined by an arcuate slot 45 therein and a stop lug 46 extending upwardly from the base B. When the dial 28 is adjusted to one of its limits of movement, as shown in Figure 3, the pointer 29 indicates "Off." In this position, the adjusting screw 41 has contacted the switch arm 19 and, it will be noted, holds the contact 24 separated from the contact 22. This condition obtains in spite of any reduction in ambient temperature tending to close the switch. When the dial 28 is rotated slightly clockwise, however, the screw 41 is positioned where it permits free actuation of the switch contacts in response to temperature changes affecting the bimetal element 17, and any adjustment for a temperature higher than 56° likewise results in the thermostat operating in the normal manner.

The adjusting screw 31 is adjusted at the factory for obtaining the desired switch action at the proper temperature indicated on the dial 28. Thereafter, the set screw may be locked with cement or sealing wax. The set screw 41 is provided in order to permit accurate adjustment, so that the switch will be held in "Off" position only when the dial 28 is rotated to such indicated position. The screw 41 likewise may thereafter be locked by cement or sealing wax.

By mounting the bracket 37 on the mounting arm A, it is obvious that I have provided a very simple means of assuring an "Off" condition in the thermostat by movement of the cam 30 to a predetermined position. The bracket 37 in no way interferes with the operation of the bimetal element except at the "Off" position of the adjusting dial.

Having described one specific embodiment of my invention together with the operation thereof, I desire it to be understood that this form is selected merely for the purpose of facilitating disclosure of the invention rather than for the purpose of limiting the number of forms which

it may assume. It is to be further understood that various modifications, adaptations and alterations may be applied to the specific form disclosed to meet the requirements of practice without in any manner departing from the spirit and scope of the present invention except as set forth in the claims appended hereto.

I claim as my invention and desire to secure by Letters Patent of the United States:

1. In a room thermostat, a supporting arm having a perforation for pivotally mounting the arm, said arm having an extension parallel to the pivot axis and terminating in a portion across the pivot axis having a second perforation for pivotally mounting said arm and aligning it at right angles to the pivot axis, a temperature responsive element mounted on said extension of said supporting arm, a switch arm carried by said temperature responsive element, switch contacts under control of said switch arm, a cam for pivotally adjusting said supporting arm and thereby said temperature responsive element, means biasing said supporting arm toward said cam, and a bracket carried by said supporting arm and engageable with said switch arm at one limit of movement of said cam, said bracket being effective to limit the movement of said supporting arm to a position retaining said contacts in a predetermined position relative to each other.

2. In a thermostat of the character disclosed, a base, a supporting arm pivotally mounted thereon, an adjusting screw carried by said supporting arm, a cam rotatable on said base, a spring biasing said adjusting screw to engage said cam, a coiled bimetallic element mounted on said supporting arm and carrying a switch arm, switch contacts controlled by said switch arm, and means carried by said supporting arm and having an adjusting screw coactable with said switch arm to hold the same in a predetermined circuit position when said cam is adjusted to one limit of its movement.

BURTON E. SHAW.
